US0D1015355S

(12) **United States Design Patent** (10) Patent No.: **US D1,015,355 S**
(45) Date of Patent: ** Feb. 20, 2024

- (54) **ELECTRONIC DEVICE WITH TRANSITIONAL GRAPHICAL USER INTERFACE**
- (71) Applicant: **Samsung Electronics Co., Ltd.**, Suwon-si (KR)
- (72) Inventors: **Eunsil Lim**, Suwon-si (KR); **Yeonjoo Jwa**, Suwon-si (KR)
- (73) Assignee: **SAMSUNG ELECTRONICS CO., LTD.**, Suwon-si (KR)
- (**) Term: **15 Years**
- (21) Appl. No.: **29/882,239**
- (22) Filed: **Jan. 12, 2023**

Related U.S. Application Data

- (62) Division of application No. 29/798,937, filed on Jul. 12, 2021, now Pat. No. Des. 987,659.

(57) CLAIM

The ornamental design for an electronic device with transitional graphical user interface, as shown and described.

DESCRIPTION

FIG. 1 is a front elevation view of a first image in a sequence of the first embodiment of an electronic device with transitional graphical user interface showing our new design with the transitional graphical user interface displayed on an inner display screen of the electronic device in an open configuration;

FIG. 2 is a rear elevation view thereof;

FIG. 3 is a front elevation view of a second image in a sequence of the first embodiment of an electronic device with transitional graphical user interface showing our new design with the transitional graphical user interface displayed on an outer display screen of the electronic device in a folded configuration;

FIG. 4 is a rear elevation view thereof;

FIG. 5 is a front elevation view of a first image in a sequence of the second embodiment of an electronic device with transitional graphical user interface showing our new design with the transitional graphical user interface displayed on an inner display screen of the electronic device in an open configuration;

FIG. 6 is a rear elevation view thereof;

FIG. 7 is a front elevation view of a second image in a sequence of the second embodiment of an electronic device with transitional graphical user interface showing our new design with the transitional graphical user interface displayed on an outer display screen of the electronic device in a folded configuration;

FIG. 8 is a rear elevation view thereof;

FIG. 9 is a front elevation view of a first image in a sequence of the third embodiment of an electronic device with transitional graphical user interface showing our new design with the transitional graphical user interface displayed on an inner display screen of the electronic device in an open configuration;

FIG. 10 is a rear elevation view thereof;

FIG. 11 is a front elevation view of a second image in a sequence of the third embodiment of an electronic device with transitional graphical user interface showing our new design with the transitional graphical user interface displayed on an outer display screen of the electronic device in a folded configuration; and,

FIG. 12 is a rear elevation view thereof.

The dashed broken lines showing an electronic device illustrate environmental subject matter and form no part of the claimed design. The remaining broken lines illustrate portions of the article that form no part of the claimed design.

The appearance of the transitional graphical user interface sequentially transitions between the images shown in FIGS. 1 and 3, FIGS. 5 and 7, and FIGS. 9 and 11, respectively. The process or period in which one image transitions to another forms no part of the claimed design.
